US00D916218S

(12) **United States Design Patent** (10) **Patent No.:** **US D916,218 S**
Lu et al. (45) **Date of Patent:** **** Apr. 13, 2021**

(54) **BALANCE BOARD**

(71) Applicant: **Hangzhou Yue Fu Si Supply Chain Management Co., Ltd.**, Zhejiang (CN)

(72) Inventors: **Zhiye Lu**, Zhejiang (CN); **Xinhan Wang**, Zhejiang (CN)

(73) Assignee: **Hangzhou Yue Fu Si Supply Chain Management Co., Ltd.**, Zhejiang (CN)

(**) Term: **15 Years**

(21) Appl. No.: **29/740,938**

(22) Filed: **Jul. 8, 2020**

(30) **Foreign Application Priority Data**

May 20, 2020 (CN) 202030235694.3

(51) **LOC (13) Cl.** **21-02**

(57) **CLAIM**

The ornamental design for a balance board, as shown and described.

DESCRIPTION

FIG. 1 is a front elevation view of a balance board, showing our design.

FIG. 2 is a rear elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a front perspective view thereof; and,

FIG. 8 is a rear perspective view thereof.

The broken line showing of portions of the balance board depicts environment and forms no part of the claim.

1 Claim, 8 Drawing Sheets
